DESIGN FOR A RESILIENT ATTACHMENT PAD FOR EYEGLASS NOSE MOUNTINGS

Sidney Tyroler, Columbus, Ohio

Application January 28, 1938, Serial No. 74,691

Term of patent 14 years

To all whom it may concern:

Be it known that I, Sidney Tyroler, a citizen of the United States, residing at Columbus, in the county of Franklin and State of Ohio, have invented a new, original, and ornamental Design for a Resilient Attachment Pad for Eyeglass Nose Mountings, of which the following is a specification, reference being had to the accompanying drawing, forming a part thereof.

Fig. 1 is a perspective view of a resilient attachment pad for eyeglass nose mountings showing my new design;

Fig. 2 is a similar view thereof taken from a different angle;

Fig. 3 is a front elevational view;

Fig. 4 is a side elevation;

Fig. 5 is a top plan view.

Figs. 1 and 2 are drawn on a greatly enlarged scale, in comparison with the other figures, for purposes of clarity.

I claim:

The ornamental design for a resilient attachment pad for eyeglass nose mountings, as shown and described.

SIDNEY TYROLER.
